(57) **CLAIM**

The ornamental design for a vehicle seat as shown and described.

DESCRIPTION

FIG. 1 is a front top left perspective view of a vehicle seat according to the new design.

FIG. 2 is a front view thereof.

FIG. 3 is a rear view thereof.

FIG. 4 is a right-side view thereof.

FIG. 5 is a left-side view thereof; and,

FIG. 6 is a top view thereof.

The portions of the vehicle seat rendered in darker gray tones are claimed. The portions of the vehicle seat rendered in light gray are for illustrative purposes and form no part of the claimed design.
